UNITED STATES PATENT OFFICE.

JAMES R. MCKINLAY, OF SEATTLE, WASHINGTON.

BOLT.

1,348,727.

Specification of Letters Patent.

Patented Aug. 3, 1920.

Application filed February 23, 1918. Serial No. 218,758.

To all whom it may concern:

Be it known that I, JAMES R. MCKINLAY, a citizen of Great Britain, residing at Seattle, in the county of King and State of Washington, have invented new and useful Improvements in Bolts, of which the following is a specification.

This invention relates to a bolt of the headless type which is intended to be employed in connecting articles the location of which renders access to the head of the bolt when in applied position, a difficult matter.

The primary object of the invention is to provide a bolt of this character which when passed through the bolt openings in the articles to be connected thereby may be retained in applied position by means of a locking key so mounted within the bolt as to obviate the necessity of removing the nut 20 from the bolt when the bolt is to be passed through or withdrawn from said opening.

Another object of the invention is to so construct the locking key and slot in the bolt in which the locking key is mounted that when the key is in locking position it will be firmly held within the slot with a portion of the key projecting beyond an end of the slot, although when it is desired to remove the bolt the key may be 30 manually forced to a position in which it will lie wholly within said slot and offer no opposition to the withdrawal of the bolt.

With these and other objects in view, the invention resides in the novel combination and arrangement of parts, which will be hereinafter described and particularly pointed out in the claim.

In the drawing:

Figure 1 is a view in side elevation of a bolt constructed in accordance with the invention and showing the same in applied position.

Fig. 2 is a view similar to Fig. 1 with the bolt shown partly in section and the locking key in retracted position.

Fig. 3 is a section on the line 3-3 of Fig. 1.

Fig. 4 is a section on the line 4-4 of Fig. 2.

Fig. 5 is a perspective view of the locking key and Fig. 6 is a similar view of the slotted end of the bolt.

Like characters of reference denote the corresponding parts throughout the several views in the drawing.

Referring now to the drawing in detail the letter A designates a pair of plates which are connected by a bolt B constructed in accordance with the invention.

The bolt B includes a cylindrical shank 10 which is passed through the bolt opening in the plates A and is threaded for a portion of its length, as at 11 adjacent one end of the bolt. The shank 10 has formed therein adjacent its other end a transversely extending slot 12 of rectangular shape in cross section. Both the side and end walls of the slot converge throughout their length from one end toward the opposite end of the slot for a purpose which will presently appear.

Engaged with the threaded portion 11 of the shank 10 is a nut 13 which is adapted to be held in contact with one of the plates A by a locking key 14 which projects beyond one end of the slot 12 and engages the other plate A. The key 14 corresponds in shape to the shape of the slot 12 and is co-extensive in length therewith, so that when the key has been manually moved to the position shown in Fig. 1 in the drawing, the key will be firmly gripped by the inclined walls of the slot and held in locking position although, the key may be readily driven to a position in which the key lies wholly within the slot 12 and offers no opposition to the withdrawal of the shank from the openings in the plates A.

When it is desired to connect a pair of plates with my improved bolt the shank of the bolt is held in the hand with the key 14 in a horizontal position and lying wholly within the slot 12. The unthreaded portion of the shank 12 is now passed through the bolt openings in the plates A and the shank given a quarter turn, so that the key 14 will under the influence of its own weight assume the position shown in Fig. 1 in the drawing. If desired the key may be forced more firmly against the inclined walls of the slot 12 with a suitable implement and thereby firmly securing the key in extended position.

When the bolt is to be removed from the openings of the bolts A the key is manually forced within the slot 12 so that it will offer no opposition to the withdrawal of the shank 10.

From the foregoing description taken in connection with the accompanying drawing it is apparent that an inexpensive bolt of the headless type has been provided which

may be advantageously used to connect articles where access to the head of an ordinary bolt would be a difficult matter.

Having thus described my invention what is claimed as new is:

The combination with a headless bolt threaded at one end, of a member having inclined plane side faces to provide a trans-

versely tapered key adapted to be removably positioned in a slot extending longitudinally of the bolt, said bolt having inclined side walls to provide a transversely tapered opening.

In testimony whereof I affix my signature.

JAMES R. MCKINLAY.
